UNITED STATES PATENT OFFICE.

FRED EDWARD FANGER, OF MEXICO, MEXICO.

ATTACHMENT FOR TYPEWRITERS.

Application filed August 9, 1922. Serial No. 530,591.

To all whom it may concern:

Be it known that FRED EDWARD FANGER, citizen of the United States, residing at Mexico, D. F., Republic of Mexico, has invented certain new and useful Improvements in Attachments for Typewriters, of which the following is a specification.

My invention relates to an attachment for typewriters, whereby the user of the machine may know at any time and instantly how many lines may still be written upon the unused portion of the paper in the machine.

One of the objects of the invention relates to an attachment for the indicated purpose embodying an element so mounted as to be revolved, with the revolving of the axle of the platen roller, relatively to a fixed pointer, and bearing peripheral symbols indicating single, double or triple line spacing.

Another object of the invention is to improve the form and arrangement of the parts entering into the attachment whereby the use of externally toothed gear elements may be employed, and whereby also the setting of the attachment is facilitated and simplified.

A further object of the invention is to facilitate the setting of the attachment whenever paper of only one length is generally used.

A still further object is to provide a construction in which the attachment can be secured to a Remington machine and at the left of the platen.

With these general objects in view, my invention consists in certain novel and peculiar features of construction and combination of parts as hereinafter described and claimed, and in order that it may be fully understood, reference is to be had to the accompanying drawing in which—

Figure 1 is a plan view of a typewriter attachment embodying my invention, illustrating the same in position on a typewriter;

Figure 2 is a longitudinal vertical section on the line 2—2 of Figure 1;

Figure 3 is a fragmentary view similar to Figure 2 but illustrating a slight modification;

Figure 4 is an end elevation with parts in section in a plane corresponding to the lines 4—4 of Figure 1;

Figure 5 is a view showing the attachment adapted for application to a Remington machine;

Figure 6 is a section on the line 6—6 of Figure 5;

Figure 7 is a section on the line 7—7 of Figure 6;

Figure 8 is a perspective view of the supplementary pointer, the dotted lines showing the spring;

Figure 9 is an elevation of a spring for holding the supplementary pointer in adjusted position.

In the illustration, the letter A indicates a portion of a platen roller, B the axle, C the knurled head on the axle for turning the same and D a fragment of the typewriter frame.

In accordance with my invention, a toothed pinion 10 is secured on the axle B of the platen roller and meshes with a larger toothed gear 11, turning the latter. Said gear 11 is in rigid relation to a shell or casing 12, the hub 13 of which is on a horizontal stud shaft 14 mounted in any suitable manner on the typewriter frame or on a part in rigid relation therewith. In the illustrated example, the inner end of the shaft 14 is screwed into a depending flange 15 on a plate 16 secured by screws 17 to the frame.

The housing 12 presents a broad periphery on which is produced in any suitable manner, an annular series of symbols, indicating single, double and triple line spacing. A pointer 18 is provided in fixed position on the frame or an element rigid therewith, said pointer, for example, being rigid with the attaching plate 16. Since the stud shaft 14 carrying the housing 12 is also supported on the flange 15 of plate 16, the securing of said plate positions the attachment for use.

A spring 19 is coiled about the stud shaft 14 and abuts at its outer end against the housing 12 tending to maintain the same in such a position on the shaft 14 as to maintain the gear 11 in mesh with the pinion 10. The spring 19 may extend at its inner end through an opening 12^a at the center of the housing 12 and around the shaft 14 as in Fig. 2, and abut at its inner end against the flange 15 or other fixed part of the typewriter; or a coil spring indicated at 19^a of Fig. 3 may terminate at its inner end within the housing 12, said inner end being suitably secured to the shaft 14 as by passing it into a transverse hole provided for the purpose in said shaft, as indicated at 14^a. In Fig. 3, the character 12^a indi-

cates a portion of the modified driven gear element corresponding with the element 11 except as to the hole 12^b which is of sufficient size only for the shaft 14 to freely pass therethrough. The housing 12, in addition to being loose on the shaft 14, in order that it may revolve about the same, is axially slidable on said shaft against the tension of the spring 19 or 19^a for setting the attachment, the setting being effected by moving the housing 12 axially to disengage the gear 11 from the pinion 10 so that the housing and said gear may be turned in either direction as desired, to set the attachment. A head 20 or equivalent means may be provided on the shaft 14 to prevent displacement of the housing 12 under pressure of the spring.

In order to facilitate the setting of the attachment whenever paper of only one length is generally used, I provide a supplementary pointer 21 to be set for indicating the number of lines which can be written on the paper. For instance, if letter size paper is ordinarily used, then the operator would set the attachment at, say 60, and set the pointer 21 opposite the number 60 in the column of figures on the drum.

After once setting, it will only be necessary to turn the drum until the pointer 21 is opposite the pointer 18, when beginning to write on a sheet of paper. This is simpler than having to look each time for the number 60 upon the drum and thus makes the setting operation much easier.

The construction devised for attaining this end comprises a toothed disc 22, which may be fastened to the drum 12 by screws 23. Interposed between the end of the drum and the said disc is a flange 24 secured in fixed relation thereto and providing a bearing for the circular portion 25 of the rotatable supplementary pointer 21. The pointer 21 may be made of springy metal and is provided with teeth 26 for engaging the toothed disc 22 to hold the said pointer from rotation when set in position. For resiliently holding the said teeth of the pointer in engagement with the disc 22, a leaf spring 27 may be interposed between the end of the drum and the pointer 21 and comprising resilient arms 28 provided with elbows 29 for increasing resiliency. As shown by dotted lines in Fig. 8, the spring and pointer may be made in one piece.

In some machines, as in the Underwood, the attachment is located on the right hand side of the machine but in a Remington it is attached to the left of the platen. A suitable construction for this purpose may comprise a plate 30 having a split sleeve which fits over the stationary part 31 on the machine and which can be securely fastened thereto by setting up the screw 32 to draw the two parts of the split sleeve to-

gether. The shaft 33 on which the drum rotates is secured to the plate 30 by a screw thread connection. The pointer 18 is rigidly secured to the plate 30 by screwing the head of the stud shaft 33 up against it. 70

Operation.

Knowing the number of lines which can be written on the particular sheet in the machine, the attachment is pushed inwards 75 to disengage the gears and rotated until the pointer 18 is opposite the said number and the pressure is relieved to cause the gears to reengage. If a certain size sheet is repeatedly used, the pointer 21 is first 80 set in position opposite the number of lines capable of being written on the sheet. This is done by forcing the teeth on the pointer out of engagement with the teeth on the disc, rotating the pointer, and then releasing it, whereupon the spring will force it into engagement with the said teeth. 85

As the platen rotates, the drum will also rotate and the numbers opposite the stationary pointer will always indicate the corresponding single, double and triple spaces which remain on the page and capable of being written on. 90

It will be obvious from the foregoing that the attachment employs the minimum number of parts, and all are of simple form; and that the securing of the attachment in position, as well as its adjustment may be quickly and conveniently effected. 95

I would state in conclusion that, while 100 the illustrated examples constitute practical embodiments of my invention, I do not limit myself strictly to the mechanical details herein illustrated, since manifestly the same can be considerably varied without departure from the spirit of the invention, as defined in the appended claims. 105

Having described my invention, what I claim as new and desire to secure by Letters Patent is: 110

1. A typewriter attachment of the class described including a toothed drive pinion adapted to be revolved with the revolving of the axle of the platen roller, a toothed driven gear element adapted to mesh with said pinion to be driven thereby, a revolute indicating element in rigid relation with said gear element, presenting at its periphery an annular series of symbols indicating varied line spacing, a stud shaft on which said gear element and said revolute indicating element are loosely mounted for jointly turning about the axis of said shaft, a fixed pointer relatively to which said indicating element revolves, and a spring coiled about said shaft and abutting said revolute element to maintain the same in position on the shaft with the driven gear element in mesh with the drive pinion, said revolute element and driven gear element being slid- 120 125 130

- able axially on the shaft to disengage the driven element and pinion to permit setting of the attachment.
2. A typewriter attachment of the class described, including a stud shaft adapted to be mounted in fixed position on a typewriter adjacent to the axle of the platen roller, a revolute indicating element loosely mounted on said shaft presenting series of symbols representing varied line spacing, a fixed pointer relatively to which said indicating element revolves, a driven gear element rigid with said revolute indicating element and coaxial therewith, said driven element and indicating element being movable axially on said shaft, drive means for said driven gear element adapted to be mounted to be turned with the turning of the platen roller, and means tending to maintain the revolute element in a position with said driven gear element in driving connection with said gear means. 30
3. A typewriter attachment of the class described, including a stud shaft adapted to be mounted in fixed position on a typewriter adjacent to the axle of the platen roller, a revolute indicating element loosely mounted on said shaft presenting series of symbols representing varied line spacing, a driven gear element rigid with said revolute indicating element and coaxial therewith, said driven element and indicating element being movable axially on said shaft, a drive pinion adapted to be mounted on the axle of the platen roller, and spring means tending to maintain the revolute indicating element in a position with the driven gear element in mesh with said pinion. 35
4. A typewriter attachment of the class described, comprising an indicating element, a toothed disc secured thereto, a pointer rotatable relative to the said disc and provided with means for engaging the same to hold the pointer in set position. 40
5. A typewriter attachment of the class described comprising an indicating element, a toothed disk secured thereto, a pointer rotatable relative to the disk and provided with teeth and means for resiliently holding the teeth of the pointer in engagement with the disk. 45

In testimony whereof I affix my signature.

FRED EDWARD FANGER.
